Specification for Design.

Patented July 11, 1916.

Application filed April 13, 1916. Serial No. 90,990. Term of patent 14 years.

To all whom it may concern:

Be it known that I, EDWIN J. OSTERBAUER, a citizen of the United States, residing at Rockford, in the county of Winnebago and State of Illinois, have invented a new, original, and ornamental Design for a Combination Kitchen Article, of which the following is a specification, reference being had to the accompanying drawing, forming part thereof.

In the drawing—Figure 1 is a face view

of a combination kitchen article providing a spoon, pan scraper, cleaver and bottle opener illustrating my new design; Fig. 2 is a rear view of the combination kitchen article; and Fig. 3 is a cross section therethrough taken on the line 3—3 of Fig. 1.

I claim:

The ornamental design for a combination kitchen article, as shown.

EDWIN J. OSTERBAUER.
